Attorney.

UNITED STATES PATENT OFFICE

WILLIAM F. HELMOND, OF WEST HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed August 5, 1929. Serial No. 383,684.

This invention relates to the carriage-mechanism of typewriting machines. The carriage is under control of the space-key at the front of the keyboard, and also has 5 the function of locking the type-keys against actuation at the completion of a line of typing.

The invention is illustrated as applied to Underwood typewriting machines. In these 10 machines the type-key-levers have hooks which co-operate with a transverse rod, to lock the keys when the rod is positioned beneath the hooks by the action of a lever which is moved by the paper-carriage.

15 Some of the aims of the invention are to improve the construction and mounting of the locking rod, and its connection with the carriage-vibrated lever. The locking rod is very light, and liable to yield under the 20 downward pressure of the keys. It has been the practice to strengthen the rod-structure by adding a rock-shaft, from which rise 25 arms that carry the locking rod. By means of the present improvements, however, the lower rod or rock-shaft is eliminated, and the device is much simplified and its cost reduced. A novel support for the middle of 30 the locking rod is provided, said support not being attached to the rod, but being secured 35 to a rock-shaft which extends across the base of the typewriter below the key-levers. It is in the form of an idle arm which is secured to said rock-shaft and rises to a point just 40 below the key-locking rod, to furnish support to the latter when it is pressed down by a key. The locking-rod device consists simply of two arms that are pivoted at their 45 lower ends upon studs projecting from the inner sides of the typewriter-base, and that 50 carry said rod at their upper ends. The rod with its arms may be fastened together, forming 55 a bail, which may be inserted as a unit in the machine by springing the rod sufficiently to permit the arms to snap upon the 60 studs.

Another feature of the invention lies in the provision of an adjustable operating lug upon the left-hand lock-rod bail-arm, this 65 operating lug being bent up from the left-hand bail-arm in position to be engaged by

the tappet which is provided on the lower end of the carriage-operated lever. An improved adjustable stop is provided for engagement by the right-hand bail-arm.

With a view to adapting the machine for 55 the use of the aforesaid carriage-supporting idle arm, changes have been made in the mounting of the space bar or key, which extends along the front of the keyboard. The ends of the space-bar are remounted upon 60 two shortened arms which are fixed upon said transverse horizontal rock-shaft lying beneath the line-locking rod. The idle arm or supporting standard on said rock-shaft is provided with a stud, which is connected by 65 a rearwardly-extending link to means for operating the carriage-feeding dog-rocker. The link pulls the dog-rocker forward, thus effecting an improvement over the usual 70 practice in Underwood machines, of pushing the dog-rocker from beneath by means of a long lever of weak construction, and subject to springing and rebounding, and hence apt to re-operate the dog-rocker devices and effect double spacing of the 75 carriage and work-sheet. By using the novel upright arm and the rearwardly-extending link, flexibility is eliminated, and there is no springiness, nor rebounding, nor double action of the spacing dogs; while the space- 80 key touch is very much lightened. The space-key rock-shaft is of heavy construction, and affords a firm support for the key-locking rod, preventing the latter from yielding. Thus a substantial key-lever lock-support 85 is provided that practically costs nothing and is very efficient and not liable to get out of order.

Difficulty has been found with key-locking 90 mechanism, that it is troublesome to locate properly in the machine, and apt to become dislocated and fail to operate. The present key-locking bail is set positively upon locating studs, and cannot be dislocated, and is reliable and durable.

95 The space-key and its rock-shaft and spring, and said upstanding idle supporting arm, are all made as a unit, and assembled upon studs that extend inwardly from the base; one end of the rock-shaft having a bore 100

that fits upon one stud, and the other end of the rock-shaft having a socket extending therefrom and having its end provided with a small bore to fit upon the other stud. The socket is secured by a set-screw. When loosened, it may be pushed along the shaft, while the other end of the shaft is placed upon its stud; whereupon the socket may be thrust out and placed upon its stud and fastened on the shaft by the screw.

Other features and advantages will hereinafter appear.

In the accompanying drawing,

Figure 1 is a sectional side elevation showing the rear portion of the train from the space-key to the typewriter-carriage.

Figure 2 is a perspective part-sectional view of an Underwood typewriting machine having the present improvements applied thereto.

Figure 3 is a front-sectional elevation showing the space-key rock-shaft and the overlying key-locking rod.

Figure 4 shows the manner of supporting the key-locking rod by means of the standard rising from the space-key rock-shaft.

Figure 5 is a perspective of the left-hand end of the key-locking frame, showing its bendable operating arm.

In an Underwood machine, keys 10 are mounted upon levers 11 forming parts of trains which operate type-bars 12 to strike a platen 13 mounted upon a carriage 14, having a rack 15 meshing with a pinion 16 to drive an escapement-wheel 17 that is controlled by spacing dogs 18, the latter being mounted upon a dog-rocker 19 having a pendent operating arm 20.

Along the front of the keyboard extends a horizontal space bar or key 21, fixed upon the forward ends of shortened levers 22, the latter extending forwardly from a heavy transverse horizontal rock-shaft 23, which is mounted upon pivot-studs 24 having stems 25 which are threaded into the sides 26, 27 of the typewriter-base.

Fixed upon the rock-shaft 23 is an upright arm 28 having a stud 29 that works in a key-hole-slot 30 formed in the forward end of a rearwardly-extending link 31, the latter provided at its rear end, at 32, with a pivotal fitting 33, into which is threaded the shank 34 of a screw having a head 35, which serves as a hook to operate the pendent arm 20 and the dog-rocker. The fitting 33 and screw 34 are relatively adjustable for lengthening or shortening the space-key train. The screw 34 slides in a mount 36, which is threaded through an arm 37 provided upon a stationary frame 38, which carries the dog-rocker and the escapement-wheel. This mount 36 has at its rear end a stop 39, to arrest the initial stroke of the dog-rocker; and this stop may be adjusted forwardly or backwardly and secured by a set-screw 40.

The downward stroke of the space-key is arrested by a stop 41 projecting from the front cross-bar 42 of the typewriter-base. The space-key is returned by a spring 43 and arrested by a stop 44, which is supported on the space-key and catches under an overhanging flange 45 provided upon said cross-bar 42.

Line-locking hooks 46, provided upon key-levers, normally clear a locking bar 47. When the line of typing is about done, a lug 48 on the paper-carriage engages a cam 49 and depresses the same, thereby rocking a transverse rock-shaft 50, from which depends a lever 51. This lever moves the line-locking rod 47 forwardly beneath the key-lever hooks 46, locking the keys. Upon the bottom of said lever 51 is carried for this purpose a tappet 52, which engages a lug 53 bent out from a left-hand arm 54 of the locking rod bail; the other end of said bail being fastened upon a companion arm 55. Said arms are pivoted upon studs 56, which project inwardly from the opposite side walls 26 and 27 of the base. The tappet 52 strikes the lug 53 and swings the rod 47 forwardly beneath the locking hooks. The lug 53 is adjustable by bending forwardly or backwardly, to secure proper co-operation between the carriage-lug 48 and the locking rod 47.

The lug 53 is made in one piece with the arm 54, by using a suitable blank in which the lug portion has an L form, as seen at Figure 5, the L being bent upwardly at 58, so that the long arm of the lug extends upwardly alongside of the arm 54 and can conveniently be bent forwardly or backwardly. The arm 55 is provided with a leaf-spring 59 to bear against a wall of the front corner post 60 of the typewriter-frame. Said arm is formed with an upward finger 61 to rest against a stop 62 in the form of an extension from a bracket 63, the latter forming part of the bichrome-ribbon mechanism.

The stop 62 may be bent forwardly or backwardly to determine the normal position for the rod 47. Said rod 47, together with its arms and their appurtenances, may be formed as a unit, and sprung in place on the studs 56, as indicated by the dot-and-dash lines, Figure 3; the rod being bowed upwardly and the lower ends of the arms made to converge between said longitudinal studs, the arms then snapping outwardly into place thereon.

The tappet 52 on the end of lever 51 strikes a cam 64 that is provided upon a bell-striker 65, to raise the striking end 66 of the same; said tappet 52 being pivoted at 67 to permit return of the lever 51 without operating the bell-striker.

To afford a support for the weak key-locking rod 47, the rock-arm 28 is extended upwardly at 68 and formed with a head 69 that extends forwardly and rearwardly beneath

the rod 47, its top edge being concentric with the shaft 23. There is a slight clearance between the edge of head 69 and the rod 47, and the head 69 moves forwardly and backwardly

5 in idleness at the operations of the space-key; but said head is always in position to intercept and support the rod 47, so that it cannot be bent down by the pressure of the hooks upon the key-levers, Figure 4.

10 A manufacturing unit is formed by the space-key 21, arms 22, shaft 23, arm 28 and spring 43, which may be assembled and then inserted bodily into the machine. At its left-hand end the shaft is made under length, and

15 a movable extension in the form of a socket 70 is slipped upon the end of the shaft. This socket has a bore in its closed end, to fit upon the left-hand stud 24. The socket is slid to the right to afford clearance to

20 permit the shaft to be placed upon the right-hand stud 24. Then the socket is slipped to the left to mount it upon the left-hand stud 24, whereupon a set-screw 71 may fasten the socket to the rock-shaft.

25 Variations may be resorted to within the scope of the invention, and portions of the improvements may be used without others.

Having thus described my invention, I claim:

30 1. In a typewriting machine having a carriage, a feeding mechanism therefor, a system of type-key-levers provided with hooks, and a rock-shaft extending across the system of key-levers beneath the same and having

35 forwardly-extending arms and a space-bar mounted upon said arms, the combination of a light rod extending across the system of key-levers and over the same to co-operate with said hooks to lock the keys, and having

40 arms fixed to the ends thereof pivotally supported by the frame of the machine, a support on said rock-shaft and independent of said rod to project up between the key-levers for supporting the middle portion of the key-

45 lever-locking rod, the middle support clearing said rod when rocked by the shaft but intercepting the rod when it is sprung down by a locked key-lever, and a connection with the carriage-feeding mechanism including a

50 stud on said middle support and a link connecting the stud with the carriage-feeding mechanism.

2. In a type-writing machine having a traveling carriage, a system of type-key-levers provided with hooks, a space-bar having a supporting rock-shaft extending across the system of key-levers and beneath the same, a light rod independent of said shaft and extending across and over the key-levers

55 and rockably supported at each end by the frame of the machine, and means operated by the travel of the carriage to rock the rod into co-operation with the hooks, to prevent the depression of the keys, the combination of

60 means mounted upon said shaft to support

the middle section of the key-lever-locking rod when said means is rocked by the space-bar, and prevent said rod from springing when any carriage-locked key is depressed.

3. In a typewriting machine having a carriage, a carriage-feeding mechanism, a system of type-key-levers to operate said feeding mechanism and provided with hooks, a space-bar having a supporting rock-shaft extending across the system of key-levers and beneath the same, a light rod independent of said shaft and extending across and over the key-levers and rockably supported at each end upon the frame of the machine, and means operated by the carriage to rock the rod into co-operation with the hooks to prevent the depression of the keys, the combination of means mounted upon said rock-shaft to support the middle section of said rod, to prevent the springing thereof to feed the carriage when any carriage-locked key is depressed.

4. In a typewriting machine having a carriage, carriage-feeding dogs, a system of type-key-levers to operate said dogs and provided with hooks, a shaft extending across the system of key-levers beneath the same and rockably supported at each end by the frame of the machine, said shaft having forwardly-extending arms with a space-bar mounted thereon to rock said shaft, and a light rod independent of the shaft and extending across the system of key-levers to co-operate with said hooks to lock the key-levers, and supported at each end by arms pivoted to the frame of the machine, the combination of a support for said key-lever-locking rod, said support mounted on said shaft to project up between the key-levers and support the middle portion of said rod without interfering with the rocking thereof by the shaft, but preventing the springing of the rod by the depression of the locked keys, and a link intermediate the middle support and the dogs, operable to feed the carriage independently of the key-levers when said levers are locked by said locking rod.

5. In a typewriting machine having a carriage, a carriage-feeding mechanism, a system of type-key-levers to operate said feeding mechanism and provided with hooks, a space-bar having a supporting rock-shaft extending across the system of key-levers and beneath the same, a light rod independent of said shaft and extending across and over the key-levers and rockably supported at each end upon the frame of the machine, and means operated by the carriage to rock the rod into co-operation with the hooks to prevent the depression of the keys, the combination of means mounted upon said rock-shaft to support the middle section of said rod, to prevent the springing thereof to feed the carriage when any carriage-locked key is depressed, the locking means including an arm

rising from said shaft to pass between the key-levers and under said rod.

6. In a typewriting machine having a carriage, a carriage-feeding mechanism, a system of type-key-levers to operate said feeding mechanism and provided with hooks, a space-bar having a supporting rock-shaft extending across the system of key-levers and beneath the same, a light rod independent of said shaft and extending across and over the key-levers and rockably supported at each end upon the frame of the machine; and means operated by the carriage to rock the rod into co-operation with the hooks to prevent the depression of the keys, the combination of means mounted upon said rock-shaft to support the middle section of said rod, to prevent the springing thereof to feed the carriage when any carriage-locked key is depressed, the locking means including an arm rising from said shaft to pass between the key-levers and under said rod, said arm having a one-way connection to operate the carriage-feeding mechanism by the depression of the space-bar without removing the middle support from the key-locking rod.
